No. 36,922.

Patented May 24, 1904.

UNITED STATES PATENT OFFICE.

ANNIE E. MANOR, OF MCKEES ROCKS, PENNSYLVANIA.

DESIGN FOR AN INKSTAND.

SPECIFICATION forming part of Design No. 36,922, dated May 24, 1904.

Application filed March 28, 1904. Serial No. 200,445. Term of patent 7 years.

To all whom it may concern:

Be it known that I, ANNIE E. MANOR, a citizen of the United States of America, residing at McKees Rocks, in the county of Allegheny and State of Pennsylvania, have invented a certain new, original, and ornamental Design for Inkstands, of which the following is a specification, reference being had therein to the accompanying drawing.

10 The figure is a perspective view of an inkstand, showing my new design.

What I claim as new, and desire to secure by Letters Patent, is—

The ornamental design for an inkstand, as herein shown.

ANNIE E. MANOR.
